(57) **CLAIM**

We claim the ornamental design for a wireless communications earpiece, as shown.

DESCRIPTION

FIG. 1 is a perspective view of a wireless communications earpiece, according to the present invention;

FIG. 2 is a front view of the wireless communications earpiece of FIG. 1;

FIG. 3 is a side view of the wireless communications earpiece of FIG. 1;

FIG. 4 is a rear view of the wireless communications earpiece of FIG. 1;

FIG. 5 is an opposite side view of the wireless communications earpiece of FIG. 1;

FIG. 6 is a top view of the wireless communications earpiece of FIG. 1; and,

FIG. 7 is a bottom view of the wireless communications earpiece of FIG. 1.
